UNITED STATES PATENT OFFICE.

FRANZ SKAUPY, OF BERLIN, GERMANY, ASSIGNOR TO GENERAL ELECTRIC COMPANY,
A CORPORATION OF NEW YORK.

INCANDESCENT LAMP.

1,160,661.

Specification of Letters Patent. Patented Nov. 16, 1915.

No Drawing.

Application filed March 9, 1912. Serial No. 682,810.

To all whom it may concern:

Be it known that I, FRANZ SKAUPY, a subject of the Emperor of Austria-Hungary, residing at Berlin, Germany, have invented 5 certain new and useful Improvements in Incandescent Lamps, of which the following is a specification.

My invention relates to incandescent lamps and particularly to lamps having metallic filaments, and its object is to prolong 10 the useful life of such lamps.

My invention consists in an improvement in the arrangement described in my former application, Serial No. 590,499, filed Nov. 3, 15 1910. In that application I disclosed means for preventing the blackening of the bulb of a metal filament lamp, such as a tungsten lamp, with a consequent prolongation of its useful life, which consisted in inserting in 20 the lamp a compound which would slowly break down during the operation of the lamp and give off in very small quantities a halogen gas such as chlorin, which would combine with the metal volatilized from the 25 filament and deposited on the bulb, and thereby produce a deposit much less light obscuring than though the deposit were formed of uncombined metal.

My present invention consists in providing another arrangement for slowly giving off the desired gas. All of the halogens will 30 serve the purposes of my invention but I prefer to use chlorin. Instead of using a compound of the chlorin or other gas, I provide a porous substance, such as a body of amorphous carbon, which contains the gas 35 which is to be given off. This arrangement has the advantage as compared with that of my former application that the rate at 40 which the gas is given off can be more exactly fixed, and the atmosphere more exactly maintained at the pressure of a first-class vacuum, or about 1/1000 of a millimeter of mercury, or less. This rate has an 45 important effect on the degree of prolongation of the lamp life. Furthermore, certain of the chemical compounds which are adapted to give up the desired halogen gas, as described in my former application, give up, 50 in addition, matter which is not easily volatilized, and which under some circumstances forms deposits which although they are light in color yet injure the appearance of the lamp. All such deposits are avoided by 55 my present invention. I may use any porous

body which is unaltered in structure or properties during the life of the lamp by being placed in the lamp, but for my invention, amorphous carbon is particularly suitable in its various forms, such as wood charcoal, animal charcoal, sugar carbon, and lamp black. The amount of gas to be given off in a unit of time may be varied within certain limits by varying the porosity and the amount of the carbon introduced. 60 The carbon may in the first place be completely saturated with the halogen or equivalent gas, and then, while the lamp is on the pump and suitably heated, a portion of the gas may be drawn off and the lamp then 65 sealed. In this way a suitable reservoir of halogen may be provided, which contains no other volatile substance, so that no light obscuring deposits prejudicial to the long 70 life and appearance of the lamp can be made 75 during the life of the lamp. Furthermore, if amorphous carbon is heated in a stream of chlorin, for example, in order to prepare it for the intended purpose, it retains absorptive power for other gases, and thus 80 may, while giving up halogen, at the same time absorb to a certain extent, harmful gases which may be given off by different parts of the lamp in operation. Thus it is 85 possible, in lamps in which, as described in my former application, metallic compounds of halogen are used, to employ carbon saturated with a halogen for the purpose of taking up objectionable decomposition products of the compound without preventing 90 the generation of halogen.

The porous substance employed in my present invention may be secured within the lamp in any suitable manner.

What I claim as new and desire to secure 95 by Letters Patent of the United States, is—

1. An incandescent lamp comprising a sealed and evacuated envelop, a metallic filament therein, and a porous substance within said envelop unaltered during the operation of the lamp, and impregnated with volatile material vaporizable during the operation of the lamp to maintain an atmosphere at the pressure of a first-class vacuum and combine with the metal volatilized from the filament 100 to form deposits on the bulb less light obscuring than similar deposits of uncombined metal would be.

2. In an incandescent lamp, a sealed and evacuated envelop, a metallic filament there- 110

in, and a body of amorphous carbon within said envelop containing a halogen vaporizable in small quantities during the operation of the lamp.

5. 3. An incandescent lamp comprising a sealed and evacuated envelop, a metallic filament therein, and a porous substance in said envelop unaltered during the operation of the lamp and containing a halogen, the metal volatilized from the filament being capable of combining with the halogen to form translucent deposits on the bulb, said halogen being vaporized during operation of the lamp to maintain in said envelop an atmosphere of said halogen at the pressure of a first-class vacuum.
4. An incandescent lamp comprising a sealed and evacuated envelop, a tungsten filament therein, and a porous body in said envelop unaltered during operation of the lamp and impregnated with a halogen vaporizable during the operation of the lamp to maintain in said envelop a halogen atmosphere at the pressure of a first-class vacuum.
5. In an incandescent lamp, a sealed and evacuated envelop, a metallic filament there-

in, and a body of amorphous carbon within said envelop containing volatile matter continuously vaporizable in small quantities 30 during the operation of the lamp and forming compounds with the metal volatilized from the filament.

6. An incandescent lamp comprising a sealed and evacuated envelop, a tungsten 35 filament therein, and a mass of amorphous carbon impregnated with chlorin and mounted in said envelop in position to maintain during the operation of the lamp an atmosphere of chlorin in said envelop at 40 the pressure of a first-class vacuum.

7. In an incandescent lamp, a sealed envelop, a tungsten filament therein, a carbon body within said envelop containing a halogen, forming tungsten compounds with vaporized tungsten under operating conditions 45 in the lamp.

In witness whereof, I have hereunto set my hand this 21st day of February, 1912.

FRANZ SKAUPY.

Witnesses:

HENRY HASPER,
WOLDEMAR HAUPT.
